FLASK

Ira R. Custer, El Paso, Tex.

Application November 16, 1931
Serial No. 575,394

9 Claims. (Cl. 22—97)

My invention relates to the art of casting and more particularly that branch of the art dealing with the casting of dental restorations. The technique for casting dental restorations for the mouth, which are formed mostly out of gold, is as follows: After making a model, one then makes a wax pattern of the different forms and designs to be cast. The pattern is then invested in a casting ring and after the mold has set the wax is burnt out, thus leaving a cavity into which gold is forced to fill the same, giving the same design as the wax formerly possessed. One frequently misses these castings after spending several hours in their preparation because the mold is colder than the gold when it is melted and forced into the same with the cast invested in a casting ring as is now the common practice. With the cast invested in a casting ring (flask) such as now is common practice, it is only practicable to heat the same to about 1500° F. for greater heat would melt the flask. By the time the flask is removed from the fire, placed in the casting machine (centrifuge) and the gold melted, the mold and flask will have cooled off about 700° F. As the gold used in dental practice fuses between 1550° and 1600° F. before the molten gold can fill all crevices of the mold cavity, it will have become chilled and the cast is missed (spoiled).

My invention, therefore, has for an object to provide means to obviate these objectionable features and provides a flask by the use of which a denser mold is produced which, when set, may be removed from the flask and heated to a much higher temperature than has heretofore been found practicable without cracking or checking. In this case the mold may be heated beyond the melting point of the gold used.

Further, my invention has for an object to provide a flask of such construction that the mold may be freed easily and quickly, a flask in which the plastic material may be used mixed as thick as possible and yet be workable, and in which the excess moisture may be squeezed out before the chemical action takes place in the plastic compound which causes it to set or become hardened.

Another object of the invention is to provide a telescopic-section flask whose sections are held extended by a removable member while the case is being embedded in the plastic investment before the squeeze is applied.

Generically, then, my invention resides in the provision of a flask composed of telescoping sections having foraminous walls through which the

water "weeps" as the sections are squeezed together in a suitable flask press.

More specifically the invention comprises a telescopic-section flask composed of walls held assembled by suitable means while the flask is being used, but capable of being knocked down or taken apart for the purpose of freeing the cast, the walls having weep holes through which excess moisture is expelled while the flask is being telescoped in a suitable flask press.

Other objects will in part be obvious and in part be pointed out hereinafter.

To the attainment of the aforesaid objects and ends, the invention still further resides in the novel details of construction, combination and arrangement of parts, all of which will be first fully described in the following detailed description, then be particularly pointed out in the appended claims, reference being had to the accompanying drawings, in which:—

Figure 1 is a perspective view of the preferred embodiment of the invention, the top plate having been removed.

Figure 2 is a central vertical longitudinal section of the same with the top plate in place.

Figure 3 is a perspective view of the parts constituting the lower section, the parts being separated.

Figure 4 is a detail perspective view of one of the side plates of the upper section together with the U-shaped braces which it carries.

Figure 5 is a detail cross section showing the manner of attaching the crucible forming core.

Figure 6 is a cross section on the line 6—6 of Figure 2 on a slightly larger scale, showing the invention in use.

Figure 7 is a side elevation of the mold removed from the flask.

Figure 8 is a perspective view of another embodiment of the invention.

Figure 9 is a vertical longitudinal section of the embodiment shown in Figure 8.

In the drawings, in which like numerals of reference indicate like parts in all of the figures, 1 represents the base which is provided with a groove 2 and is suitably perforated as at 3 to provide weep holes. Set into the groove 2 are end and side plates 4 and 5. These plates have their meeting edges mitered as at 6 and they are secured to the base 1 by suitable screws 9 (preferably thumb screws or cap screws as indicated). The side and end plates are stepped as at 7 to provide portions which telescope correspondingly stepped portions of the upper section of the flask. The parts 1, 4 and 5 constitute the lower section

of the flask. The end and side plates of the lower section of the flask are also perforated at suitable intervals as at 8 to provide weep holes.

The upper section consists of end plates 10 and 5 side plates 11, each having stepped portions 12 to telescope with the lower section, the lower edges of the plates 10 and 11 being bevelled as at 13 so that the upper section will easily find itself on the lower section. The plates 10 and 11 are also 10 perforated as at 14 to provide weep holes and their abutting edges are mitered as at 15.

Upper and lower U-shaped braces 16 and 17 respectively are secured at 18 to the side plates of the upper section and extend over the end 15 plates of the upper section to which they are detachably secured by suitable cap or thumb screws 19.

In order to hold the upper and lower sections apart and prevent their telescoping while the 20 pattern is being invested, I provide a U-shaped spring clip 20 which embraces the lower section above the step 7 and holds the upper section from telescoping. The member 20 has a handle 21 so that it may be removed as soon as the flask 25 has been put in the press preparatory to the application of the squeezing pressure.

22 designates a crucible forming core which is carried by one of the side plates of the upper section to which it is attached by suitable screws 30 23, the crucible forming core being perforated as at 24.

25 designates the mold which is provided with the crucible portion 26 and in which the wax pattern 27 is invested. 28 is a hole which is 35 cut from the crucible 26 to the beginning of the wax pattern preparatory to the melting out of the wax and the replacement thereof by the molten gold. 29 is a flange or shoulder formed on the mold 25 by reason of the bevel step 12 40 of the upper section of the mold.

30 designates the apertured cover plate of the flask.

Instead of having the flask rectangular and made knocked down as shown in the first six 45 figures of the drawings, a flask of circular form may be employed. When such a flask is made according to this embodiment of my invention, it consists of a lower section 31 and an upper section 32, the sections having telescoping portions 33 and a cover 34, the cover and sections 32 and 31 being perforated at 35 to provide weep holes.

By the use of my invention, particularly the 55 collapsible embodiment shown in Figures 1 to 8 inclusive, I am enabled to mix my investment as thick as I can and still be workable. Having filled the flask with the thick composition and embedded the wax pattern therein, I remove the member 20 and apply a squeezing pressure up 60 and down in a suitable flask press, thus squeezing out the excess moisture through the weep holes and condensing the investment material, so that when the chemical action of hardening takes place a more dense and a harder mold is produced, one which can stand heating to high temperatures.

Squeezing out and eliminating the excess water gives a more congealed, compact and harder cast which will withstand a greater amount of heat 70 without contracting or checking than has heretofore been the case.

By making the flask collapsible it can be readily disassembled in order to free the mold from the flask. So in heating the mold it is not 75 necessary to place the flask in the oven with

it as is now the case with ordinary casting rings.

From the foregoing description, taken in connection with the accompanying drawings, it is thought the complete construction, operation and advantages of my invention will be clear to those skilled in the art.

What I claim is:

1. A flask comprising an upper and a lower section telescopically connected together and having foraminous walls.

2. A flask comprising telescopic sections each composed of separable walls, and means to hold the walls in assembled relation while the sections are being telescoped together, said walls being foraminous.

3. A flask having an upper and a lower section, said lower section comprising side and end walls and a base, means detachably securing the side and end walls to the base, the upper portion of the side and end walls being stepped, the upper section of the flask comprising side and end walls, the lower portions of which are stepped to telescope the upper portions of the lower section, a cover plate over the walls of the upper section and means detachably holding the side and end walls of the upper section together.

4. A flask having an upper and a lower section, said lower section comprising side and end walls and a base, means detachably securing the side and end walls to the base, the upper portion of the side and end walls being stepped, the upper section of the flask comprising side and end walls, the lower portions of which are stepped to telescope the upper portions of the lower section, a cover plate over the walls of the upper section and means detachably holding the side and end walls of the upper section together, said last named means comprising members carried by one pair of upper walls and embracing the other pair, and screws securing said members to said other pair of walls.

5. A flask comprising telescoping sections and a crucible-core secured in one of said sections, said sections and core being composed of foraminous walls.

6. A flask having an upper and a lower section, said lower section comprising side and end walls and a base, means detachably securing the side and end walls to the base, the upper portion of the side and end walls being stepped, the upper section of the flask comprising side and end walls, the lower portions of which are stepped to telescope the upper portions of the lower sections, a cover plate over the walls of the upper section and means detachably holding the side and end walls of the upper section together, said means to secure the side and end walls to the base of the lower section comprising a groove in the base into which said walls set, and screws passed through the base into said walls to hold them in the groove.

7. A flask having an upper and a lower section, said lower section comprising side and end walls and a base, means detachably securing the side and end walls to the base, the upper portion of the side and end walls being stepped, the upper section of the flask comprising side and end walls, the lower portions of which are stepped to telescope the upper portions of the lower section, a cover plate over the walls of the upper section and means detachably holding the side and end walls of the upper section together, and a U-shaped member insertible between the upper and lower sections in the stepped portions of the lower section for the purpose described.
